FIG. 1

FIG. 2

FIG. 3

The side not shown is substantially a mirror image of the side shown in FIGURE 2.

The dominant features of my design reside in the portions illustrated in solid lines.

For purposes of illustration the wheels are omitted from FIGURE 2.

I claim:

The ornamental design for a bottle or similar article, as shown and described.
